(57) **CLAIM**

The ornamental design for a vehicle rear bumper cover, as shown and described.

DESCRIPTION

FIG. 1 is a front and side perspective view of a left vehicle rear bumper cover (the right vehicle rear bumper cover being a mirror of the left vehicle rear bumper cover and is not shown);

FIG. 2 is a side elevational view of the vehicle rear bumper cover;

FIG. 3 is a rear perspective view of the vehicle rear bumper cover;

FIG. 4 is a front and opposite side perspective view of the vehicle rear bumper cover;

FIG. 5 is a top plan view of the vehicle rear bumper cover; and,

FIG. 6 is a bottom plan view of the vehicle rear bumper cover.

Shading is used to illustrate the curvature of the part and not color.
